UNITED STATES PATENT OFFICE.

JOHN P. CLARK, JR., OF JACKSON, MICHIGAN.

WINDOW.

SPECIFICATION forming part of Letters Patent No. 424,179, dated March 25, 1890.

Application filed September 5, 1889; Serial No. 323,025. (No model.)

To all whom it may concern:

Be it known that I, JOHN P. CLARK, Jr., of Jackson, in the county of Jackson and State of Michigan, have invented a new and useful Improvement in Windows, of which the following is a full, clear, and exact description

The object of my invention is to provide an improved means for adjusting, sealing, and securing the sashes of a window in their case-
ment or frame.

To this end my invention consists in the construction and combination of parts, as hereinafter described, and indicated in the claims.

Reference is to be had to the accompanying drawings, forming a part of this specification, in which similar letters of reference indicate corresponding parts in all the figures.

Figure 1 is a front elevation of the inside of a window and its frame. Fig. 2 is a sectional side elevation of the window, taken on the line 2 2 in Fig. 1. Fig. 3 is a sectional plan view of the window and its frame, taken on the line 3 3 in Fig. 1; and Fig. 4 is an enlarged detached view of a side rail of the window, in section on the line 4 4 in Fig. 1, showing the preferred method of securing the glass in the window.

The frame of the window is composed of the stiles A, cap-piece A', and sub-sill A², joined together in the usual manner. The inner faces of the stiles A are furnished with bead-strips a a', secured thereto, forming abutments for the sash-frames and shutters, the latter named being omitted from the drawings. The upper and lower sash-frames are constructed in a similar manner; hence it will be sufficient to describe one, which will answer for the pair. Each frame consists of the side bars b, held together by top rails b' and bottom rails b². On the inner edges of the frame longitudinally-grooved strips c are secured. The grooves therein receive and retain a metal frame or shoe c', (see Fig. 4,) which shoe is adapted to encompass a light of glass B. A sufficient space is permitted between the double parallel walls of the shoes c' to permit continuous gum washers c² to be introduced on each side of the light of glass B, so that said sheets of glass will be relieved of strains and avoid breakage that might result

from expansion of the glass, contraction of the frame, or other causes of similar nature.

The upper rails b' in each sash are notched, as at d, so that overlapping ends d' are produced, which bear upon the ends of the shorter side bars b, and are secured thereto by screws, which retain all parts intact after the glass is in place.

The upper and lower sash-frames are so proportioned to the dimensions of the window-frame that they will neatly fit therein when closed. The joint between the meeting-rails of the upper and lower sash is produced by rabbeting the adjacent edges, thus producing offset mating shoulders thereon, as at g, (see Fig. 2,) which will obstruct the passage of cold air, and, if preferred, a piece of thin gum cloth g' may be introduced, which will effectually seal the joint.

The meeting-rails b' b² of the sashes are hinged together on the inner surface thereof, as at h, which will permit the lower or upper sash to be swung inwardly.

When both sashes are closed, the upper sash is secured from falling inwardly by a spring-catch i, that engages a latch-plate i', which is secured to the lower surface of the cap-plate A', a downward movement of the bolt of the catch releasing the upper sash in an obvious manner.

An inward inclination at any desired angle may be afforded the upper sash by the proper location of the slotted links m, which are pivotally affixed by their lower perforated ends m' to the stiles of the window-frame, their slotted upper portions engaging the inserted screw stops or pivots n, which are embedded in the edges of the side bars b of the sash-frame.

The lower sash when opened can be upwardly folded against the upper sash and there retained by a spring-catch k, that is secured on the inner face of the cap-piece A' of the window-frame, a wear-plate k' on the outer face of the lower rail b² engaging said catch k when the lower sash is so adjusted.

In order to provide for the secure closing of the lower sash and prevent cold air or dust from entering the apartment, a cap-sill C is mounted upon the sub-sill A², and thereto secured so as to have a limited vertical vibra-

tion by the longitudinally-central screw o , which is inserted in a slightly-elongated orifice in the cap-sill and firmly introduced into the sub-sill.

5. The cap-sill C is provided with a depending skirt-piece C', that forms a finish for the window-sill on the inner face of the same, and to press the cap-sill C upwardly against the lower edge of the lower sash-frame in a yielding manner the springs p are secured upon the sub-sill A² below the cap-sill, against which they impinge, so as to afford an elastic seat therefor, which provision will effectually close the crevice below the lower sash and by pressure against the inner edge of the sash seal the window at this point against inward draft of cold air or intrusion of dust.

Having thus described my invention, I claim as new and desire to secure by Letters Patent—

1. The combination, with a window-frame having vertical bead-strips attached and projecting from the sides oppositely, of two sash-frames having their horizontal meeting edges hinged to permit inward folding of either sash-frame, a spring-catch for the top sash latching upwardly, a spring-catch for the lower

sash latching downwardly, and two slotted links which are pivoted to the sides of the window-frame and have sliding engagement with the upper sash-frame, substantially as set forth. 30

2. The combination, with a window-frame and two sash-frames hinged together, the meeting edges of the sash-frames being rabbed to afford mating offset shoulders, and a spring-catch for each sash-frame, of two slotted link-bars pivoted to the window-frame and to the upper sash-frame, so that the upper pivots may slide in the link-slots, substantially as set forth. 35

3. The combination, with a window-frame and two sash-frames hinged together, of a yielding cap-sill which bears upwardly against the lower sash-frame, substantially as set forth. 40

4. The combination, with a window-frame and two sash-frames, of a cap-sill loosely secured to the sub-sill of the window-frame, and a spring-support for the cap-sill, substantially as set forth. 45
